Attorney.

UNITED STATES PATENT OFFICE.

ARTHUR FOLGER, OF LEAVENWORTH, KANSAS.

FORMER FOR MAKING BOXES.

SPECIFICATION forming part of Letters Patent No. 467,986, dated February 2, 1892.

Application filed March 7, 1891. Serial No. 384,179. (No model.)

To all whom it may concern:

Be it known that I, ARTHUR FOLGER, a citizen of the United States, residing at Leavenworth, in the county of Leavenworth and State 5 of Kansas, have invented certain new and useful Improvements in Formers for Making Boxes; and I do declare the following to be a full, clear, and exact description of the invention, such as will enable others skilled in the 10 art to which it appertains to make and use the same, reference being had to the accompanying drawings, and to the letters of reference marked thereon, which form a part of this specification.

15 My invention relates to formers for making berry and other analogous boxes in which the bottom is separate from the sides, the said two parts being made usually of flexible strips of wood or veneering and joined 20 together.

The object of the invention is to provide means for holding the bottom to a former while the strip comprising the sides is formed or shaped over said "former" and secured to 25 the bottom.

It also has for its object the provision of means for holding the several parts and the arrangement of said means, whereby the operation of making the box is greatly facilitated and expedited.

30 For the accomplishment of the foregoing and such other objects as may hereinafter appear the invention consists in the construction and the combination of parts hereinafter described and claimed, reference being had to the accompanying drawings, forming a part hereof, and in which—

Figure 1 is a perspective view of the invention. Fig. 2 is a side elevation with the 40 former-block in section. Fig. 3 is a front view of the former-block.

In the drawings, the letter A designates the front legs, and B the rear legs, of the structure, the front legs being preferably extended 45 higher than the rear legs, as illustrated, so as to constitute standards serving to support parts hereinafter specified. The legs preferably spread outwardly from their upper to their lower ends and are braced transversely 50 by the cross-bars C and D. The front and

rear legs are connected together by a horizontal bar or board E, the front end of which preferably extends between the front legs A and rests upon the cross-bars C. This bar or board is suitably secured to its place. Next 55 to the extended portions of the legs A is placed a transverse plate or board F, whose width is preferably the length of the strips that will constitute the sides of the box, and consequently it projects beyond one side of 60 the board E, as illustrated. Projecting from the upper end of the board F is a former G, which in outline or cross-section may be of any desired shape or configuration corresponding to the shape the box is to bear. 65 It is, however, preferably oblong and formed with angular corners a, as shown, so as to impart an oblong shape to the box, with eight sides, as illustrated. Opposite to this former, so as to coat therewith, is a plunger or follower H, which serves to press the bottom of the box against the face of the former and assist in holding the same against it while the sides of the box are being formed and secured to the bottom. This follower or holder 70 is secured to an arm I, which is suitably supported, so as to swing back and forth in order to move the holder to or from the former. This may be effected by connecting it to the board E by a hinge J, the arm extending 75 through an opening K, made in the board, so that it may extend beneath the board and be connected to suitable operating mechanism. The arm is passed through the board at a point back from the plate or board F, so as 80 to leave a space between the arm and board F sufficient to form a seat or rest L, on which will be piled the strips M from which the sides of the box will be made, while the portion of the board E back of the arm will constitute a seat N for the operator of the machine.

At a suitable place beneath the board E there is pivoted a foot-lever O, it being illustrated as pivoted at one end to one of the 95 front legs of the device, and as extending from one side to the other of the machine. This lever has a suitable connection with the arm I, say, by means of a chain or strap P, which will pass over a sheave or other guide 100

Q. This construction is such that by pressing down on the foot-lever the lower end of the arm is drawn forward and the upper end thrown backward, so as to carry the follower 5 or holder away from the face of the former.

Suitable means are employed for restoring the arm and holder to their normal position against the face of the former when the pressure on the foot-lever is released. For this 10 purpose it is preferred to use a spring, which may be a coiled spring R, one end being secured to the arm I and the other end to a suitable part—say to one of the cross-bars D of the machine. By this arrangement the 15 holder is thrown with force against the face of the former, for a purpose hereinafter appearing, and held there until the foot-lever is again depressed to move back the holder.

Above the board F is formed a shelf S, the 20 same preferably resting on top of the extended portions of the front legs A and being firmly secured thereto. This shelf is provided, preferably, at the left-hand end with a two-sided compartment T for the blanks U, which will 25 form the bottoms of the boxes, and at the other end with a receptacle V for the brads or tacks that will be used for securing the two ends of the side strips together after being shaped on the former.

30 A cleat or guide-strip W is placed at one end of the plate or board F, so as to guide the side-forming strips as each one is moved upward by hand preparatory to shaping it on the former. This enables the strips to be

35 expeditiously guided to their places on the former, so that their ends will meet at the point on the top of the former, where is located a metallic plate X for clinching the ends of the brads or fastenings as they are forced 40 through the lapping ends of the side strips.

The face of the former is provided with one or more small sharp-pointed projecting pins Y, so that when the bottom-forming strip is placed against the same and the plunger or 45 holder H is thrown by the force of spring R against the bottom strip the latter is driven firmly against the face of the former, and the pins thus caused to penetrate through the bottom strip, so as to assist the follower in

50 holding it firmly against the former while the side strip is being pressed into shape and position around the edges of the bottom strip. The corners b of the bottom strip extending beyond the square edges or corners a of the former, it is obvious that when the side strip is pressed around the former the projecting corners b of the bottom strip will penetrate through the side strip (see Fig. 1) and serve 55 to hold the bottom in place after the ends of the side strip are secured by their fastenings.

A stop c will be arranged so as to limit the upward movement of the foot-lever as it is drawn back by the recoil of spring R. A bar 60 Z is shown as extending upward from the cross-bar C and as being secured to it and at its upper end to the triangular-shaped brace-

block d, extending from between the upper ends of the front legs. This, however, is merely for bracing purposes and may be omitted.

In action the operator straddles the seat N, with one foot pressing on the foot-lever Q, so as to throw the follower or holder H back from the face of the former. He lifts with the left hand one of the bottom strips U from the pile and places it against the face of the former. He then moves his foot from the lever, when the spring R throws the follower or holder forward, causing it to press the bottom strip against the face of the holder with 70 the pins Y penetrating through the strip. At the same time he lifts one of the side strips M from the pile, guiding it by the guard W until it strikes against the under side of the former, when he bends the two ends, causing 75 them to shape to the former, and laps their ends over the metallic clinching-plate of the former. He next drives the fastenings, taken from the receptacle on the top shelf, through the side strip, and the ends of the fastenings 80 are clinched by the metallic plate of the former. He next presses down the foot-lever, which draws back the holder and allows the box in its finished state to be slipped from off the former, and the operation of forming 85 another box to proceed as before. It will thus be observed that the boxes are made with the greatest expedition and every part essential in forming the same is in most convenient 90 position for expeditious work.

I have described with particularity the several parts illustrated in the drawings, but without meaning to restrict myself to the details thereof, as it is obvious that many alterations can be made therein without departing from the essential features of the invention.

Having described my invention and set forth its merits, what I claim is—

1. In a box-forming machine, the combination, with the former and a movable arm carrying a holder adapted to press the bottom of a box against the face of the former, of a rest beneath the former for the side-forming strips and a vertical guide to one side of said rest for the end of the side-forming strip to bear against for directing said strips in moving the same to the former, substantially as and for the purposes set forth.

2. In a box-forming machine, the combination of a former provided on its top with a metallic plate for clinching the side-strip fastenings and having on its front face projecting pointed pins to penetrate the bottom strip, in combination with a spring-actuated arm carrying a holder to press the bottom strip against the face of the former and cause said pins to penetrate the bottom strip, substantially as and for the purposes set forth.

3. In a box-forming machine, the combination, with the board E, forming a seat and suitable supports therefor, of a former, an

arm hinged to said board and extending above and below it and carrying at its upper end a holder adapted to press the bottom-forming strip against the face of the former, a lever 5 for moving said holder-carrying arm away from the former, and a spring for throwing the holder carried by said arm against the former on releasing pressure from said lever,

substantially as and for the purposes set forth.

In testimony whereof I affix my signature in presence of two witnesses.

ARTHUR FOLGER.
